UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

Application filed August 5, 1921, Serial No. 490,086. Renewed June 7, 1924.

To all whom it may concern:

Be it known that I, JOSEPH BECKER, a citizen of the United States, residing in Pittsburgh, in the county of Allegheny and State of Pennsylvania, have invented a new and useful Improvement in Coking Retort Ovens, of which the following is a specification.

This invention comprehends improvements of general utility in the coking retort oven art; and also comprehends certain improvements especially applicable to coking retort ovens of the well known cross regenerative type exemplified in the patent to H. 15 Koppers No. 818,033, dated April 17, 1906, and in my prior Patent No. 1,374,546, dated April 12, 1921.

The invention has for objects the provision of a coking retort oven having as important characteristics; an improved flue construction that permits a considerable reduction not only in the length but also in the cross sectional dimensions of the horizontal or bus flues located at the top of the vertical flame flues and connecting a plurality of the latter with each other; and, as a feature that may be secured by the above structural improvements, a novel system of control of the flow through the flame flues of the heating walls, permitting flow in the same direction through all the flame flues of each heating wall, with discharge of the flow from the burning flues through the down-flow operating flues through duct means of reduced area that is especially designed to promote uniformity in distribution of the flow throughout the heating walls.

With regard to the novel flue and out-flow duct construction, for example, a pair of horizontal flues in each heating wall may be substituted for the usual single horizontal flue which extends from end to end of the heating wall, each horizontal flue of the pair being connected by duct means constituted of a plurality of channels with the corresponding horizontal flue of the next adjacent heating wall. With such horizontal flue and out-flow duct construction, each horizontal flue need communicate with only approximately half the total number of flues of the heating wall and each channel is only required to receive part of the flow from its communicably connected horizon-

tal flue; consequently the dimensions of the 55 horizontal flues and out-flow duct means or channels may be considerably decreased or reduced because of the consequent reduction in volume of flow which must be maintained through each horizontal flue and each out-flow channel. The above stated reduction in size of the horizontal flues and out-flow channels is an important advantage for the reason that it enables a considerable thickening and strengthening of the walls of the 60 oven structure in the region of the horizontal flues. Moreover, the improved flue and duct construction permits an increase in the height of the flame flues, with a corresponding increase in the height of the coking chambers so that the latter may be made 65 narrower in width, a development greatly facilitating the coking of high volatile coals, and yet having adequate provision for taking care of the increased volume of 70 combustion products, without making it necessary to enlarge the horizontal flue dimensions and out-flow duct means to sizes inconsistent with adequate strength of the 75 wall construction in the region of such flues. 80 The improvements of the invention are furthermore of great importance in oven batteries fired with extraneously-derived gas, such as producer gas, since the employment of such gas results in an increased volume 85 of combustion products and adequate flue spaces must be provided to collect and feed to the down-flow operating flues this increased volume of combustion products. By the invention, the flue and out-flow duct 90 construction may be adequately accommodated to such increased volume of combustion products without introducing elements of weakness into the wall structure.

In addition to the general objects recited 95 above, the invention comprehends a novel regenerator construction and system of flow therethrough and through the flues, promoting uniformity of distribution, and has for other objects such other improvements 100 or advantages in construction and operation as are found to obtain in the structures and devices hereinafter described or claimed.

In the accompanying drawings, forming 105 a part of this specification and showing, for purposes of exemplification, a preferred form and manner in which the invention may be embodied and practiced, but with-

out limiting the claimed invention to such illustrative instance or instances:

Figure 1 is a composite side elevational view showing both the pusher side and the coking side of a coke oven battery having in its construction some of the heating walls provided with rectangular flues and others with triangular flues, the battery embodying features above specified and equipped 10 with the improvements of the present invention;

Fig. 2 is a transverse sectional elevation taken through a coking chamber and regenerator of the coke oven battery illustrated in 15 Fig. 1, showing the duct connections of the rectangular flues with the regenerators:

Fig. 3 is a composite vertical sectional elevation taken longitudinally of the coking oven battery in planes indicated by the lines 20 H—H, K—K, C—C, and D—D of Figs. 2 and 4;

Fig. 4 is another vertical sectional elevation taken transversely of the coke oven battery in planes indicated by the line F—F of 25 Fig. 3, showing the duct connections of the triangular flues with the regenerators;

Fig. 5 is a composite vertical sectional elevation taken transversely of the coke oven battery through a rectangular-flued heating 30 wall in planes indicated by the lines A—A and B—B of Fig. 3; and

Fig. 6 is another composite vertical sectional elevation taken transversely of the coke oven battery through a heating wall 35 in planes indicated by the lines G—G and E—E of Fig. 3.

The same characters of reference designate the same parts in each of the several views of the drawings.

40 In the embodiment illustrated in the drawings the invention is incorporated in a combination coke oven battery, i. e., a battery having provision for being operated either with producer gas as a fuel, or with

45 coke oven gas burned in an atmosphere of ordinary preheated air such as is utilized in ordinary coking ovens, or with coke oven gas burned in an atmosphere containing both air and a neutral gaseous diluent which is introduced into the flame flues separately from the air. A combination coke oven battery having these features is described and

50 claimed in my application for patent for coking retort oven filed April 23, 1920, Serial No. 376,126. For convenience the present description will be confined to the present illustrated embodiment of the invention in such a combination oven battery; the novel features and improvements made

55 by the invention are susceptible of other applications such, for example, to ordinary so-called "coke ovens" employing coke oven gas as the fuel, or ordinary so-called "gas ovens" employing an extraneously derived gas, such as producer gas, as

the fuel; hence, the scope of the invention is not confined to the specific embodiment herein described as an illustrative example.

Referring to the drawings; there are illustrated views of a coke oven battery or plant of the by-product type, having features above specified; said oven battery embodies in its construction a plurality of cross-wise elongated heating walls 11, 11 and a plurality of intermediate cross-wise elongated vertical coking chambers 12, 12. The heating walls 11 form the side walls of the respective coking chambers 12, as shown more particularly in Figs. 1 and 3, and, in the present instance, are directly supported by the heavy supporting or pillar walls 13, 13 which extend cross-wise of the battery and are located beneath the respective heating walls 11, 11. These pillar walls, together with other walls, hereinafter described, collectively form the main support for the entire structure of the oven battery and are themselves supported upon a flat mat or platform 19 which constitutes the sub-foundation on which the entire battery rests.

The coal to be coked is charged into the several coking chambers or ovens through charging holes 14 located in the top 15 of the oven battery and positioned directly above the ovens or chambers 12, as shown in Figs. 2, 3 and 4. These charging holes 14 are equipped with the usual removable covers, which are removed during charging of the individual ovens or coking chambers 100 and are placed in position to close the tops of such coking chambers during the entire coking or distilling operation. The gases of distillation pass from the tops of the several coking chambers 12 through gas outlets 16 and thence through ascension pipes (not shown) into the usual gas collecting main which carries the distillation products to the by-product recovery apparatus.

Heat for coking the charges of coal in the several ovens or chambers 12 is derived from the heating walls 11, which, as above mentioned, extend cross-wise of the battery at the sides of the coking chambers. Referring now more particularly to Figs. 3, 5 and 6, 115 each heating wall 11 is constituted of a plurality of flame or combustion flues, of which the rectangular flues are designated by the reference character R, and the triangular flues by the reference character T. The triangular flues are of the type exemplified in my prior Patent No. 1,312,301, dated August 5, 1919 and in the prior patent of Joseph Van Ackeren, No. 1,312,372, dated August 5, 1919. Whether rectangular or triangular, the flame flues of each heating wall are operatively disposed into a single group, that is to say, all of the flame flues of each heating wall operate concurrently as up-flow or down-flow operating flues, as will be herein- 130

after more fully explained. When the flame flues on one side of a coking chamber are burning, that is to say, operating for up-flow, the flame flues on the opposite side of the same coking chamber are operating for down-flow to permit exhaust of the waste gases. Consequently heating is maintained continuously from end to end on one side of a charge of coking coal in each coking chamber, the heating being applied to the full length of one side of each charge during an entire operating period and, then, after reversal, being applied to the full length of the opposite side of the charge until the subsequent reversal is effected.

The crosswise regenerators 18 of the coke oven or battery are located at a lower level than the aforesaid heating walls 11 and coking chambers 12, and, in the present instance extend in parallelism between the pillar walls 13 and the heavy supporting walls, hereinafter described. Located in the middle lengthwise vertical frame of the coke oven battery is a vertical partition 19, as shown in Figs. 2 and 4, which partition extends all the way up from the mat of the battery to the bottom of the overlying coking chamber and from one to the other of the pillar walls 13 and the other walls which are between the pillar walls. The regenerators which are respectively located on opposite sides of the battery extend inwardly to said partition 19 and are separated thereby, as clearly shown in Figs. 2 to 4. This arrangement permits control from opposite sides of the battery of the flow from the regenerators, thereby assisting the novel flue arrangement, in promoting uniformity of distribution.

Each regenerator 18 is a chamber containing open brick work, commonly called checker work and indicated at 20, with distributing sole channels 21, underneath such checker work, the channels forming the soles of such chambers and opening up into the checker work. As shown in Figs. 2 and 4 each regenerator of the pair of transverse regenerators 18 is preferably provided with a vertical baffle 31 extending only part way up to the top of the regenerator and positioned substantially midway between the inner and outer ends of the regenerator. There is also preferably a pair of sole channels 21 for each regenerator, one sole channel leading to that region of the regenerator which is between the baffle 31 and the partition 19, and the other sole channel of the pair leading independently to the outer region of the regenerator which is located between the baffle 31 and the outer side wall of the battery. This construction provides an important improvement for the reason that it enables separate control of the flow through the interior region of each regenerator, with the result that the flow

through the interior regions of the several regenerators may be equalized relatively to the flow through those portions of the regenerators which are located nearer to the side walls of the battery, thereby promoting uniformity of distribution of the flow.

In the present embodiment of the invention, a heavy vertical gas-tight supporting wall 22 extends directly beneath the coking chamber in parallelism between each two pillar walls 13, and such supporting walls 22 provide two generators G and H located respectively on the opposite sides of such walls 22 and between adjacent pillar walls 13. The several walls 22 also have the function with the pillar walls 13 of supporting the weight of the battery superstructure. This supporting wall construction provides two series of crosswise extending parallel gas-tight load carrying walls located below the coking chambers and intermediate heating walls, the supporting walls of one series 13 being directly beneath the heating walls, and the supporting walls of the other series 22 being directly beneath the coking chambers. The walls 22 which are beneath the coking chambers are constructed and function not as mere partitions, commonly employed, but as true load-carrying gas-tight walls, permitting relatively different pressures to be maintained in the checker work chambers on the opposite sides of said walls or the flow of different media in the checker work chambers separated by the walls without leakages from one checkerwork chamber into another and without danger of mixing in the checkerwork chambers gases which must be kept separate in this region of the battery.

The regenerators G and H are heated in alternation by the hot combustion products that draw off from the flame or combustion flues hereinbefore mentioned and then impart such heat to the media that they feed into these flame flues; in the present instance, the flow through the regenerators G and H between each two adjacent pillar walls is maintained concurrently in opposite directions, for example, when the flow is passing up through a regenerator G down-flow is being maintained concurrently through the other regenerator H. The pairs of regenerators H, G that are respectively located on opposite sides of the pillar walls 13 are provided with a series of ducts 23, the ducts of each pair of regenerators leading respectively to flame flues 17 of the same heating wall, whereas the ducts 23 of the next adjacent pair of regenerators lead respectively to the flame flues of the next adjacent heating wall, as clearly shown in Fig. 3. With this construction, each flame flue 17 communicates by ducts 23 with adjacent separate regenerators H, G, and the

flow through the regenerators H, G which are respectively located on the opposite sides of a pillar wall 18, is maintained concurrently in the same direction, that is to say, both said regenerators are either operating for in-flow or for out-flow.

In the present embodiment of the invention, the entire series of flame flues 17 of each heating wall 11 is either burning or 10 operating for down-flow to convey the waste products to the regenerators beneath and consequently the regenerators align on opposite sides of the central longitudinal partition 19 operate concurrently for flow 15 in the same direction and in the same manner. The reversal in flow through the flame flues 17 on opposite sides of the coking chamber, and their communicably connected regenerators may thus be said to take 20 place longitudinally of the oven battery instead of transversely thereof, as has heretofore been a common practice of this art. The reversal of the oven is effected at the 25 end of an operating period determined by practice and by means of any preferred type of reversing mechanism. The function of such reversal is as follows: The regenerators that prior to the reversal operated as in-flow regenerators become out-flow regenerators and the out-flow operating regenerators become in-flow operating regenerators; the up-burning series of flues 30 switches function with the down-flow series of flues of the next adjacent heating wall and the supply of gas is turned off 35 from the previously up-burning flues and turned on into the mains of the previously down-burning flues.

Each flame 17 of each heating wall has 40 at its top a port or opening 24 for draft and the passage of combustion products or waste gas from the flame within the flue. These ports 24 open up into horizontal or bus flues 25 formed in the heating walls 45 and connecting all of the vertical flues which communicate with such horizontal flues 25 by means of the ports 24. According to the invention there are in each heating wall a plurality, in the present instance 50 two, of such horizontal flues 25 positioned end to end with respect to each other and respectively located on the opposite sides of the central dividing line L. By reason of the fact that there is a plurality of such 55 horizontal flues 25, these flues are not required to be of so great capacity as that necessary in present practice, and consequently the cross-sectional area of each horizontal flue may be reduced proportionately with the length of such flue, with the 60 result that the thickness and strength of the heating walls are substantially increased in the region of the horizontal flues. Moreover because of the fact that each horizontal flue 25 communicates with a substan-

tially reduced number of vertical flues, in the present instance half of the flues of the heating wall, uniformity of distribution of the flow in the vertical flues and the communicating regenerators is greatly promoted. 70

As shown in Figs. 5 and 6, each such horizontal flue 25 tapers toward its outer end in such manner that the smallest cross-sectional area of each flue is located at its end adjacent to the outer side wall of the battery. The tapering portion of the channel serves to distribute the flow equally through the several vertical flues 17 that are located toward the outer side of the battery 80 and with which flues such horizontal flue communicates. As shown, the two horizontal flues 25 of each heating wall are each communicably connected with the corresponding horizontal flues of an adjacent heating wall by duct means comprising a pair of passageways or out-flow channels 26 and 27. The channels 26 preferably open up into the mediate portions of their respective connected horizontal flues 25, as shown in Figs. 5 and 6, whereas the channels 27 are located at and open up into the extreme inner ends of their respective connected horizontal flues. With this construction each pair of horizontal flues of each heating wall is communicably connected with the pair of horizontal flues of the next adjacent heating wall, by mediate channels or ducts and interior channels or ducts corresponding to each pair of connected flues, the mediate channels 26 receiving the flow from and directing the flow of the flues 17 that are located toward the outer side walls of the battery and the interior channels 27 receiving the flow from 105 and directing flow into flues 17 that are located in the remotely interior regions of the battery. Preferably that portion of each horizontal flue 25 which extends between the pair of channels 26 and 27 is not 110 tapered but has substantially parallel walls, in order to permit equal distribution of the flow through both channels 26 and 27. Inasmuch as each horizontal flue 25 is connected by a plurality of channels or ducts with the corresponding flue of the next adjacent heating wall, the individual channels may be made of reduced size, with corresponding strengthening and thickening of the wall structure in the region of such channels. With the above construction the entire flow from the heating wall, within the flues of which combustion is being maintained, passes downwardly through all of the flues of the next adjacent heating wall 120 and each reversal operation is accompanied by a reversal in direction in flow through all of the flues of each heating wall.

The draft through the ports 24 may be regulated by means of the usual movable

- dampers or sliding bricks 28 positioned in the ordinary way in the bottoms of the horizontal flues 25 and adapted to be reached by access flues 29 which extend 3 from the top of the horizontal flues 25 in each heating wall to the top 15 of the battery, there being an access flue affording communication to each flame or combustion flue in each heating wall.
- 10 Extending cross-wise of the battery in each pillar wall 13 and located beneath the heating wall 11 thereabove, is a pair of gas supply channels 30 and 32. These channels 30 and 32 are for the purpose of supplying coke oven gas to the several flame flues on each side of the central line L, and to accomplish this end, the channel 29 communicates with the individual flues 17 on one side of said line L by means of ducts 33 that lead 20 from such channel 29 individually into the bottoms of individual flues and the channel 32, which supplies the several flues which are located on the opposite sides of the before-mentioned dividing line L, communicates therewith by means of similarly connecting ducts. Within the several ducts are disposed the usual nozzles 34. The supply of coke oven gas to the respective channels 30 and 32 is derived from coke oven gas mains 30 of the usual type and respectively located on the opposite sides of the battery and extending longitudinally therealong. Suitable means is provided for admitting or cutting off the supply of gas with respect to each 35 pair of channels 30 and 32, it being understood that the gas supply is either concurrently maintained in or concurrently shut off from both channels of each pair.
- For operating the battery alternatively 40 with the use of a special generator gas, such as producer gas as the fuel, the several regenerators H may be optionally connected with a producer gas main by mechanism such as is disclosed in my before-mentioned application, Serial No. 376,126, so that the producer gas may be directed into such of the regenerators H as are operating for in-flow and conveyed through these regenerators into burning flame flues 17.
- 50 The operation of the retort oven or battery, when using a special generator gas, such as ordinary producer gas, is as follows: The supply of coke oven gas to the coke oven gas main and to all of the channels 30 and 32 is cut off. A supply of producer gas is permitted to flow into the alternate regenerators H, such as are operating for in-flow and passing through said regenerators is pre-heated before being delivered into the burning flame flues. During the in-flow of the producer gas through such alternate regenerators H, waste gas from the down-burning flues is flowing out into the intermediate regenerators G as well as through the regenerators H that are intermediate such alter-
- 55 nate regenerators. In the alternate regenerators G in-flow of air is maintained and passing upwardly through such regenerators finally enters the burning flame flues to support the combustion of the producer gas that 71 is delivered thereto by the alternate regenerators H. On reversal of the flow the in-flow operating regenerators become out-flow regenerators and concurrently the out-flow operating regenerators become inflow regen- 74 erators.
- In operating the battery with coke oven gas in the ordinary manner, the supply of producer gas to alternate regenerators H is shut off and air is permitted to flow into such 88 regenerators in place of the producer gas. During coke oven gas operation a supply of coke oven gas is maintained in the channels 30 and 32 for feeding the burning flues. The reversing mechanism is operated at each 85 reversal to place all of the in-flow operating regenerators in communication with the outer air and concurrently, all of the out-flow operating regenerators in communication 90 with the exhaust.
- A further mode of operation is with coke oven gas as a fuel, combined with a supply of neutral gaseous diluent to the up-burning flues. In so operating the battery, the supply of producer gas is turned off and the 95 supply of coke oven gas is turned on. Instead, however, of permitting air to flow into alternate regenerators of the series H that serve for producer gas during the latter operation, waste gas is permitted to flow 100 into said regenerators and be delivered thereby to the up-burning flues. The admission into each of the up-burning flues of a supply of neutral gaseous diluent, such as waste gas, is effective to lengthen greatly the flames 105 within such flues and to prevent the localization of the hottest flame temperature in the extreme lower portions of the flues.
- The invention as hereinabove set forth is embodied in a particular form of construction but may be variously embodied within 110 the scope of the claims hereinafter made.
- I claim:
1. In a coking retort oven, in combination: a plurality of coking chambers; heating walls contiguous to such coking chambers and respectively constituted of vertical combustion flues; a plurality of horizontal flues in each heating wall and respectively connecting a plurality of combustion flues of 115 their respective heating walls; each horizontal flue being also communicably connected with the corresponding horizontal flue of an adjacent heating wall by duct means located at the inner portion of the horizontal flue and also by duct means located between the ends of such horizontal flue, each horizontal flue being tapered only from its immediate duct means toward its outer end; and cross-wise regenerators parallel with the 120

- coking chambers and the heating walls, such regenerators being communicably connected in pairs with the combustion flues of a single heating wall, and each regenerator having a baffle between its opposite ends and separate sole channel means individually communicably connected with those portions of the regenerator that are located on the opposite sides of said baffle; substantially as specified.
- 5 2. In a coking retort oven, in combination: a plurality of coking chambers; heating walls contiguous to such coking chambers and respectively constituted of vertical combustion flues; a plurality of horizontal flues 70 in each heating wall and respectively connecting a plurality of combustion flues of their respective heating walls; each horizontal flue being also communicably connected with the corresponding horizontal flue of an adjacent heating wall by duct means located at the inner portion of the horizontal flue and also by duct means located between the ends of such horizontal flue; and cross-wise regenerators parallel with the coking 75 chambers and the heating walls, such regenerators being communicably connected in pairs with the combustion flues of a single heating wall, and each regenerator having a baffle between its opposite ends and separate sole channel means individually communicably connected with those portions of the regenerator that are located on the opposite sides of said baffle; substantially as specified.
- 10 3. In a coking retort oven, in combination: a plurality of coking chambers; heating walls contiguous to such coking chambers and respectively constituted of vertical combustion flues; a plurality of horizontal flues 80 in each heating wall and respectively connecting a plurality of combustion flues of their respective heating walls; each horizontal flue being also communicably connected with the corresponding horizontal flue of an adjacent heating wall by duct means located at the inner portion of the horizontal flue and also by duct means located between the ends of such horizontal flue, each horizontal flue being tapered only from its mediate duct 85 means toward its outer end; and regenerators communicably connected with said flues; substantially as specified.
- 15 4. In a coking retort oven, in combination: a plurality of coking chambers; heating walls contiguous to such coking chambers and respectively constituted of vertical combustion flues; two horizontal flues in each 90 heating wall and respectively connecting a plurality of combustion flues of their respective heating walls; each horizontal flue being also communicably connected with the corresponding horizontal flue of an adjacent heating wall by duct means located at the inner portion of the horizontal flue and also by duct means located between the ends of such horizontal flue; and cross-wise regenerators parallel with the coking 95 chambers and the heating walls, such regenerators being communicably connected in pairs with the combustion flues of a single heating wall, and each regenerator having a baffle between its opposite ends and separate sole channel 100 means individually communicably connected with those portions of the regenerator that are located on the opposite sides of said baffle; substantially as specified.
- 20 5. In a coking retort oven, in combination: a plurality of coking chambers; heating walls contiguous to such coking chambers and respectively constituted of vertical combustion flues; a plurality of horizontal flues 105 in each heating wall and respectively connecting a plurality of combustion flues of their respective heating walls; each horizontal flue being also communicably connected with the corresponding horizontal flue of an adjacent heating wall by duct means located at the inner portion of the horizontal flue and also by duct means located between the ends of such horizontal flue; and cross-wise regenerators parallel with the coking 110 chambers and the heating walls, such regenerators being communicably connected in pairs with the combustion flues of a single heating wall, and each regenerator having a baffle between its opposite ends and separate sole channel 115 means individually communicably connected with those portions of the regenerator that are located on the opposite sides of said baffle; substantially as specified.
- 25 6. In a coking retort oven, in combination: a plurality of coking chambers; heating walls contiguous to such coking chambers and respectively constituted of vertical combustion flues; a plurality of horizontal flues 120 in each heating wall and respectively connecting a plurality of combustion flues of their respective heating walls; each horizontal flue being also communicably connected with the corresponding horizontal flue of an adjacent heating wall by duct means located at the inner portion of the horizontal flue and also by duct means located between the ends of such horizontal flue; and cross-wise regenerators parallel with the coking 125 chambers and the heating walls, such regenerators being communicably connected in pairs with the combustion flues of a single heating wall, and each regenerator having a baffle between its opposite ends and separate sole channel means individually communicably connected with those portions of the regenerator that are located on the opposite sides of said baffle; substantially as specified.
- 30 7. In a coking retort oven, in combination: a plurality of coking chambers; heating walls contiguous to such coking chambers and respectively constituted of vertical combustion flues; and cross-wise regenerators parallel with the coking 130 chambers and the heating walls, such regenerators being communicably connected in pairs with the combustion flues of a single heating wall, and each regenerator having a baffle between its opposite ends and separate sole channel means individually communicably connected with those portions of the regenerator that are located on the opposite sides of said baffle; substantially as specified.
- 35 8. In a coking retort oven, in combination:

- tion: a plurality of coking chambers; heating walls contiguous to such chambers and respectively constituted of combustion flues: and cross-wise regenerators parallel with the communicating chambers of the heating walls, each regenerator having a baffle between its opposite ends and separate sole channel means individually communicably connecting in parallel those portions of the regenerator that are located on the opposite sides of said baffle; substantially as specified.
9. In a coking retort oven, in combination: a plurality of coking chambers; heating walls contiguous to such chambers and respectively constituted of combustion flues; and regenerators parallel with the communicating chambers and the heating walls, each regenerator having a baffle between its opposite ends and separate sole channel means individually communicably connecting in parallel those portions of the regenerator that are located on the opposite sides of said baffle; substantially as specified.
10. In a coking retort oven, in combination: a plurality of coking chambers; heating walls contiguous to such coking chambers and respectively constituted of vertical combustion flues; a plurality of horizontal flues in each heating wall; and separate interior and mediate duct means communicably connecting each horizontal flue with the corresponding horizontal flue of an adjacent heating wall; substantially as specified.
11. In combination with a coking chamber, flued heating walls respectively constituting the opposite side walls of said coking chamber, the flues of pairs of the heating walls being communicably connected with each other by separate interior and mediate duct means extending over the top of the coking chamber; reversible means for maintaining combustion in alternation in said heating walls, the exhaust gases produced by the combustion in one heating wall being drawn off by the other, and reversible regenerators respectively communicating with said heating walls; substantially as specified.
12. In a coking retort oven, in combination: a plurality of coking chambers; heating walls contiguous to such coking chambers and respectively constituted of vertical combustion flues; horizontal flow duct means in each heating wall; and separate interior and mediate duct means communicably connecting each horizontal flow duct means with the corresponding horizontal flow duct means of an adjacent heating wall; substantially as specified.
13. In a coking retort oven, in combination: a plurality of coking chambers; heating walls contiguous to such coking chambers and respectively constituted of vertical combustion flues; horizontal flow duct means in each heating wall; separate interior and mediate duct means communicably connecting each horizontal flow duct means with the corresponding horizontal flow duct means of an adjacent heating wall; and regenerators serving said heating walls; substantially as specified.
14. In a coking retort oven, in combination: a plurality of coking chambers; heating walls contiguous to such coking chambers and respectively constituted of vertical combustion flues; horizontal flow duct means in each heating wall; separate interior and mediate duct means communicably connecting each horizontal flow duct with the corresponding horizontal flow duct means of an adjacent heating wall; and cross-regenerators respectively serving said heating walls and reversible in pairs longitudinally of the battery.

In testimony whereof I hereunto set my hand this 26th day of July, 1921.

JOSEPH BECKER.
